(57) **CLAIM**

The design for a housing for storage tank quantity measurement and wireless data transmission electronics, as shown and described.

DESCRIPTION

FIG. 1 is a perspective view of the design;
FIG. 2 is a front elevational view of the design;
FIG. 3 is a rear elevational view of the design;
FIG. 4 is a left side elevational view of the design looking rightward in FIG. 2; the right side elevational view being a mirror image thereof;
FIG. 5 is a top plan view of the design; and,
FIG. 6 is a bottom plan view of the design.
The subject matter delineated by the broken lines in FIG. 6 does not form any part of the claimed design.
